DESCRIPTION

FIG. 1 is a front perspective view of a RESPIRATORY MASK WITH AIR DELIVERY ADAPTER showing our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a rear perspective view thereof;

1 Claim, 6 Drawing Sheets
